COTTON'S PATENT AND OTHER STRAIGHT
BAR KNITTING MACHINEWilliam Arthur Cooper, Loughborough, England,
assignor to William Cotton Limited, Lough-
borough, EnglandApplication February 10, 1945, Serial No. 577,164
In Great Britain October 7, 1943

4 Claims. (Cl. 66—96)

This invention concerns Cotton's Patent and other straight bar knitting machines and particularly those equipped with automatic welt-turning apparatus. During the turning of the welt, a welt rod is inserted and take-up straps are connected to the ends of the rod by hooks. These straps extend to a beam roller that is rotated (usually by a weight) so that the straps are wound on to it and the fabric being knitted is drawn away from the needles. As the straps wind on, they naturally build up the effective diameter of the roller, so that equal angular movement of the latter tends to cause a progressively greater linear draw-off movement of the straps. An even greater irregularity is produced when the welt rod itself passes on to the beam roller. In order that the straps may be unwound, they are connected by cords or other flexible connections to another roller that is driven from the beam roller and at the appropriate time reverse rotation is imparted to the beam roller so that the cords are wound on to the second roller and the straps wound off the beam roller and the hooks are thereby re-positioned to receive a welt rod during the production of the next stocking. It will therefore be appreciated that during the production of a stocking there is a tendency for the linear rate at which the straps are wound on to the beam roller to differ from the linear rate at which the cords are unwound from the second roller.

According to this invention, in a Cotton's Patent or other straight bar knitting machine having take-up straps or equivalent flexible connecting means for attachment to a welt rod or other device for drawing the fabric away from the needles, a rotary member (e. g. a beam roller) to which the straps are attached and which is rotatable in one direction to wind up the straps and to draw off the fabric and in the reverse direction to unwind the straps (e. g. so that they may be attached to the welt rod or the like), a second rotary member coupled to the first one, and flexible connections extending from said straps to the second rotary member and arranged to be wound on to the latter in said reverse rotation so as to withdraw the straps from the first member and to be unwound from it during the fabric take-up rotation of the first member, there is provided a spring coupling connecting the two rotary members together.

The foregoing and other features of the invention set out in the appended claims are incorporated in the construction which will now be de-

scribed with reference to the accompanying drawings in which

Figure 1 is a cross sectional view through the relevant parts of a Cotton's Patent knitting machine;

Figure 2 is a further cross-sectional view showing additional details, while

Figure 3 is a plan, partly in section, showing the spring coupling and associated parts.

Figure 1 illustrates the application of the invention to Cotton's Patent knitting machine having automatic welt-turning apparatus whereof the welt bar is indicated at 10, and having needles 11, needle bar 12, sinker head 13, sinkers 14, beam roller shaft 15, and table 16. The said shaft is biased in the take-up direction by means indicated diagrammatically at 17. A sprocket 18 on the beam roller shaft is connected by an endless chain 19 to a sprocket 20 freely mounted on a second horizontal shaft 21 at the rear of it. This sprocket 20 is coupled to its shaft 21 by a spring coupling indicated generally at 22. Fixed to this second shaft 21, alongside sprocket 20, there is a boss 23 having a laterally-projecting pin 24 that projects into an arcuate slot 25 in the said sprocket 20. A tension spring 26 extends from said pin 24 inside an annular groove 27 in the said sprocket, to an anchorage 28 such as another pin on the latter. Cords 29 extend, from the ends of the usual take-up straps 30 (which are attached to the beam roller 31 and are provided with hooks 32 for the welt rod 33) over guide rollers 34 to rollers 35 on the second shaft 21, and the direction of the spring 26 is such that when take-up rotation is imparted to the beam roller 31 the necessary cord-unwinding motion is imparted from the second-mentioned sprocket 20 to the second shaft 21 through the spring tension. This permits the boss 23 (under the pull of the cords) gradually to overtake the second sprocket 20 until the pin 24 reaches the front end (the right hand end in Figure 2) of the slot 25 to drive "solid" so that the linear rate at which the cords 29 unwind is the same as that at which the straps and fabric are wound on to the beam roller.

Reverse rotation is imparted to the beam roller by, for example, the hand wheel indicated at 36 and is communicated to the shaft 21 by the said front end of the slot 25 pressing against pin 24.

Preferably the chain-and-sprocket gearing is a reduction gearing, the sprocket 18 on the beam roller shaft having, for example, 23 teeth and the second sprocket 20 having 25 teeth.

I claim:

1. In a Cotton's Patent or other straight bar knitting machine having take-up straps or equivalent flexible connecting means for attachment to a device for drawing the fabric away from the needles, a rotary member to which the straps are attached and which is rotatable in one direction to wind up the straps and to draw off the fabric and in the reverse direction to unwind the straps (e. g. so that they may be attached to the welt rod or the like), a second rotary member coupled to the first one, and flexible connections extending from said straps to the second rotary member and arranged to be wound onto the latter in said reverse rotation so as to withdraw the straps from the first member and to be unwound 15

from it during the fabric take-up rotation of the first member; and spring coupling connecting the two rotary members together.

2. A machine according to claim 1, wherein the second rotary member is driven from the first through the spring coupling.

3. A machine according to claim 1, having the coupling arranged to provide a solid drive after a predetermined yield.

4. A machine according to claim 1, wherein the second rotary member is driven from the first through the spring coupling, said machine having the coupling arranged to provide a solid drive after a predetermined yield.

W. A. COOPER.
